UNITED STATES PATENT OFFICE.

PERCY E. BARKER, OF CLEVELAND, OHIO, ASSIGNOR OF ONE-HALF TO THOMAS B. VAN DORN, OF CLEVELAND, OHIO.

WASHING MACHINE.

Application filed October 12, 1921. Serial No. 507,250.

This invention relates to improvements in washing machines.

The objects of this invention are to provide a washing machine of the rotary cylinder type in which the cylinder or drum is rotated without the use of the customary gears for delivering power to the drum; and more specifically to provide the drum with an annular series of pockets dipping into the fluid contained within the casing in which at least a part of the fluid is displaced from the pockets successively by a fluid of less specific gravity, as for example, air; furthermore, to provide a structure in which the air or other fluid is allowed to circulate from the air pipe and pockets up through the drum; and to provide also means for forcing a current of the cleansing fluid contained within the casing through openings in the ends of the drum so as to increase the circulation of the fluid through the materials contained within the drum.

Other objects of this invention will appear from the following description and claims when considered together with the accompanying drawings.

Fig. 1 is a vertical transverse section of my improved device; Fig. 2 is an end view of the drum; Fig. 3 is a side view partly in elevation and partly in section; and Fig. 4 is an elevation of the delivery end of the air pipe.

The outer casing 1 which may be of any suitable form is provided with the removable cover 2 and the bearings 3 for support of the trunnions 4 on the two ends of the cylinder or drum 5 which is adapted to rotate within the casing and to be partly submerged in the cleansing fluid contained therein. The drum comprises the end wall members 6 which are shown as of dish shape and which are for the most part imperforate, except for the perforations indicated at 7. The blades 8 suitably mounted on the end walls 6 form pockets which open in opposite directions on the two ends of the drum and together with the perforations 7 constitute what might be termed "louvers" which are adapted to cause circulation of the cleansing fluid through the openings and from one end to the other of the drum as it is rotated through the fluid. The main wall of the drum comprises an annularly arranged series of channel shaped plates or strips 9 whose ends are suitably secured to

the ring members 9^a seated in the circumferentially extending flanges 6^a on the end walls 6. The channel members 9 are each provided with a pocket 10 and an extended portion 11 which extends over the adjacent 60 pocket of the next channel member. These members are properly spaced from each other so as to provide a passage for communication between each pocket and the inside of the drum, this passage being indicated at 12. A passage is indicated at 13 for communication between the outside of the drum and the pockets 10 and through these communicating passages there is established a circulation of cleansing fluid 70 and air from the outside to the inside of the drum. The drum is provided also with a cover indicated at 14 which comprises a number of the channel members 9 with sectors of the ring members 9^a and which may 75 be secured in closed position by any suitable locking means.

A pipe 15 which leads from a source of air under pressure has connection at its lower end portion with the nozzle 16 which 80 extends part way along the main wall of the casing and which is adapted to deliver a jet of air through nozzle 16 suitably secured to the inner wall of the casing on the opposite side of the aperture 17. The nozzle 16 is of tapering form with its small end beveled as indicated at 18 so as to direct the jet of air somewhat in an upward direction. As shown in the drawing, the mouth portion 16' is located in close proximity to 90 the outside of the drum so that the jet of air delivered through the mouth will impinge in turn against the channel members 9 so as to displace at least a portion of the fluid from the pockets.

From the above it will be seen that the jet of air will displace at least a portion of the fluid from one of the pockets 10 opposite the mouth, the air forced into the pocket being indicated at 20. The result of such 100 substitution is that the load is lightened at this point and a tendency is therefore created for this part of the drum to rise and to bring the next pocket opposite the mouth. Like substitution of air for cleansing fluid 105 will take place as the next pocket is moved to such position, while at the same time the air will be permitted to gradually escape through a communicating passage 12, as indicated at 12^a, to the inside of the drum and 110

up through the fluid to the air space thereabove. The decrease in the volume of air in the several pockets is indicated in the drawings. It will be noted that the jet of air is discharged into the pockets of the drum at a point in one of the lower quadrants of the path of travel of the drum and that the liquid level is at a point corresponding approximately with the topmost point in the path of travel of the "louvers".

Thus I have avoided the use of the customary gears for a drive connection for the drum and at the same time I have obtained a circulation of air and cleansing fluid through the materials within the drum, which means a highly efficient cleansing of the materials.

What I claim is:

1. A washing machine, comprising a fluid containing casing, a drum rotatable on a horizontal axis therein, the peripheral wall of said drum being provided with a series of externally opening pockets having imperforate inner walls, each of said pockets being provided with an extended wall portion which partially covers and thereby restricts the external opening of an adjacent pocket, and means for supplying a gaseous medium to said pockets so as to cause the rotation of the drum.

2. A washing machine, comprising a fluid containing casing, a drum rotatable on a horizontal axis therein, the peripheral wall of said drum being provided with a series of externally opening pockets having imperforate inner walls, said pockets being spaced apart so as to provide passages therebetween, each of said pockets being provided with an extended wall portion which partially covers the external opening of an adjacent pocket, said extended wall portions co-operating with the passages between the pockets in the establishment of communication between said pockets and the inside of the drum, and means for supplying a gaseous medium to said pockets so as to cause the rotation of said drum.

3. A washing machine, comprising a fluid containing casing, a drum rotatable on a

horizontal axis therein, the peripheral wall of said drum being provided with a series of externally opening pockets having imperforate inner walls, said pockets being spaced apart so as to provide passages therebetween, and each of said pockets being provided with an extended wall portion, said extended wall portions co-operating with the passages between the pockets in the establishment of communication between said pockets and the inside of the drum, and means for supplying a gaseous medium to said pockets so as to cause the rotation of said drum.

4. A washing machine comprising a washing fluid containing casing, a drum journaled in said casing, said drum having a series of pockets arranged about the axis of said drum and in communication with the washing fluid in said casing, said pockets having baffled passages communicating with the inside of said drum, and means for substituting a gaseous fluid for at least a part of the washing fluid in said pockets when they occupy positions in the lower quadrant of said drum so as to create a rotary motion of said drum, said gaseous fluid being of such nature as to maintain substantially fixed volume in the presence of the washing fluid.

5. A washing machine comprising a washing fluid containing casing, a rotary drum mounted in said casing, the main wall of said drum including a plurality of spaced wall sections so as to provide means of communication for fluids through the wall of the drum, said wall sections being each provided with a pocket opening outwardly and having communication with the inside and outside of the drum, and means for substituting a gaseous fluid for at least a part of the washing fluid in said pockets when they occupy positions in the lower part of the path of travel of the drum, said gaseous fluid being of such nature as to maintain substantially fixed volume in the presence of the washing fluid.

In testimony whereof I hereby affix my signature.

PERCY E. BARKER.
